Des. 219,277
Patented Nov. 24, 1970

219,277

PORTABLE ANIMAL ENCLOSURE

Marshall E. Benjamin, 300 E. 10th St.,
Borger, Tex. 79007

Filed Oct. 7, 1969, Ser. No. 19,445

Term of patent 14 years

Int. Cl. D30—01

U.S. Cl. D30—1

FIG. 1 is a perspective view of a portable animal enclosure;

FIG. 2 is a top plan view of the invention;

FIG. 3 is a side elevation of the invention;

FIG. 4 is a front elevation of the invention; and

FIG. 5 is a rear elevation of the invention.

I claim:

The ornamental design for a portable animal enclosure, as shown and described.
